FIG. 1

FIG. 6

6 ← = FIG. 2

FIG. 3

FIG. 4

FIG. 5

FIG. 1 is a front, top and right side perspective view of a portable transmitter, showing our new design;

FIG. 2 is a bottom plan view;

FIG. 3 is a rear elevational view;

FIG. 4 is a left side elevational view;

FIG. 5 is a top plan view; and

FIG. 6 is a fragmentary vertical cross-sectional view thereof, taken substantially on the line 6—6 in FIG. 2.

The drawing figures are stippled to indicate a contrast in appearance.

We claim:

The ornamental design for a portable transmitter, as shown and described.
